Primary Examiner — Lauren D McVey*Assistant Examiner* — Sarah L Smith**CLAIM**

The ornamental design for a toy, as shown and described.

DESCRIPTION

FIG. 1 is a perspective view of a toy showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion 9 in FIG. 1.

The evenly broken lines shown in the drawings depict portions of the toy that form no part of the claimed design. The dash-dot broken lines shown in FIG. 1 and FIG. 9 illustrate the bounds of the enlarged portions and form no part of the claimed design.
